GEARED POWER UNIT

Walter P. Schmitter, Milwaukee, Wis., assignor to
The Falk Corporation, Milwaukee, Wis., a corporation of Wisconsin

Application November 23, 1936, Serial No. 112,306

8 Claims. (Cl. 74—420)

This invention relates to a central geared driving unit for multiple oilwell pumps.

It is common practice in the oil fields to drive several pumps from a single operating head connected thereto through suitable cables. A geared power unit for this purpose is shown in Patent No. 2,054,782, to Percy C. Day, issued September 15, 1936, comprising an operating head mounted upon a crank arm supported at the top end of a vertical shaft driven at a low speed through appropriate gearing.

Several important objections may be noted to the power units commonly in use for this purpose. One of the chief of these is the difficulty of assembling and mounting such large units under field conditions. It is common practice to set the lower portion of the housing of such a unit into a foundation of concrete or the like, and then assemble the remainder within it. Because of the fact that the upper portion of the housing serves also as a mounting means for the gear shafts, and because of the fact that the heavy crank arm and the heaviest gear are carried on the same shaft on opposite sides of the upper half of the housing, it has heretofore been necessary to assemble all of the gears together with the upper half of the housing, and drop them as a unit into the lower part of the housing. Because of the tremendous size and weight of such units, however, this manner of assembling has been a matter of the greatest difficulty, and the cost of dismantling the unit for repairs has been almost prohibitive. Moreover, when a change of the entire unit is necessary, it has been necessary to chop the housing out of its concrete foundation.

In addition, in units heretofore in use, the plan of assembly and the mounting have been of such a permanent nature that changes in stroke or in power capacity have been of the greatest difficulty. To change the stroke of the operating crank, it is usually necessary to disassemble the unit and to remove and replace the entire main crank shaft, which is made integral with the crank arm. In order to change the power capacity of the unit, it is often necessary to replace the unit with one of a different size, heretofore usually requiring breaking of the housing out of the foundation, and rebuilding the foundation to accommodate the different sized unit.

An object of the present invention is to provide an improved self-contained geared power unit of the type described.

Another object is to provide such a unit which

may be more easily and readily assembled under field conditions.

Another object is to provide such a unit in which the various operating parts may be easily removed for repairs or replacement.

Another object is to provide an improved means for mounting such a unit.

Another object is to provide such a unit in which the moving parts may be readily and easily adjusted relative to each other to attain most efficient service and prevent excessive wear.

Other objects and advantages will appear, expressed or implied, in the following description of a driving unit constructed in accordance with the present invention.

In the accompanying drawings:

Figure 1 is a vertical longitudinal sectional view of a driving unit embodying this invention.

Fig. 2 is a top plan view of the unit shown in Fig. 1.

Fig. 3 is an end view of the unit shown in Fig. 1 with the sole plate for mounting it shown in section.

Fig. 4 is a bottom view showing the method of attaching the lower portion of the housing to the sole plate.

Fig. 5 is a fragmentary sectional view on the line 5—5 of Fig. 2, showing the arrangement of the oil pump.

The general arrangement of the power unit, shown in the drawings, is similar to that of the patent identified above, and includes a housing 10 comprising a lower casing 11 and a cover 12. The lower casing 11 forms a reservoir 13 which is filled with oil to the level indicated by the line 14.

Journalled at one end of the housing 10 is a high speed driving shaft 15 carrying at its inner end a bevel pinion 16. Shaft 15 is mounted upon appropriate bearings 17 and 18 carried by the housing 10.

Likewise journalled in the housing 10 is a vertical intermediate shaft 19, carrying at its center a pinion 20. Mounted on this shaft above the pinion is a bevel gear 21 which meshes with 45 and is driven by the bevel pinion 16.

In order to provide proper adjustment and to prevent back lash between the bevel pinion 16 and the bevel gear 21, provision is made for adjusting the shaft 19 longitudinally of its vertical axis. For this purpose the lower bearing 22 of the shaft is made a simple roller bearing in which the shaft may slide longitudinally. At its upper end, however, the shaft 19 is supported by the double end-thrust tapered roller bearings 23 and 24.

24. These bearings are mounted in a sleeve 25 fitted into an opening 26 in the cover 12 of the housing 10. An internal ring 27, screwed to the inside of the sleeve 25 near its top, serves to 5 secure the bearings 23 and 24 within the sleeve.

The sleeve 25 is freely movable longitudinally in the supporting cover 12, but is positioned and supported therein by an outer ring 28, screwed around the top of the sleeve. This ring 28 rests 10 upon the cover 12, so that by simply turning the ring 28, the sleeve 25 and the shaft 19 supported thereby may be raised or lowered. By this means, the gear 21 may be accurately positioned with respect to the gear 16 and readily adjusted from 15 time to time to compensate for wear.

A bearing cover 29 is provided which will completely cover all of the bearing parts after adjustment thereof, and provide a tightly sealed 20 head to insure proper working of the lubricating 20 system.

It will be noted that the shaft 19 is made symmetrical with respect to the pinion 20, so that in case of wear the bevel gear 21 may be removed and the shaft turned end for end and re- 25 assembled.

Also mounted in the housing 10 is a crank shaft 30 carrying a large gear 31 which meshes with and is driven by the pinion 20 upon the intermediate shaft 19. Like the shaft 19, the shaft 30 30 may be adjusted longitudinally of its vertical axis, being moveable in its lower roller bearing 32 and being supported at its upper end by the double end thrust tapered roller bearings 33 and 34. These bearings are likewise mounted in a 35 sleeve 35 and securely positioned therein by an inner ring 36 screw threaded inside of the top thereof.

The sleeve 35 is mounted in an opening 37 in the cover 12 of the housing, but is slideable vertically within the opening 37. The sleeve 35 and the shaft 30 are supported from the cover 12 of the housing by the ring 38 which is screwed around the outside of the top of the sleeve, and whose lower edge bears against the cover 12. It 40 is thus possible to adjust the shaft 30 and its gear 31 vertically with respect to the housing, by turning the ring 38 on the sleeve to raise or lower the sleeve 35.

Upon the top end of the shaft 30 is formed a 50 flange or disc 39 to which a crank arm may be removably secured. It will be noted that this disc 39 has been made of a size small enough to pass through the opening 37 in the cover 12 of the housing. It is thus possible to assemble the entire 55 gear train within the lower casing 11, and to thereafter slip the cover 12 of the housing over the shaft bearings, after which the rings 28 and 38 may be screwed into place and the shafts 19 and 30 raised or lowered thereby to secure exactly 60 the right adjustment of the gears.

Carried at the top of the crank shaft 30 is the 65 crank arm 40 releasably but firmly secured to the flange or disc 39 by bolts 41 and by the key 42. A wrist pin 43, mounted near the outer end of the crank 40, supports the operating head 44, which is mounted upon the wrist pin by the two end thrust tapered roller bearings 45 and 46. The head 44 is provided with the usual peripheral series of holes 47 for receiving conventional driving connections through which the several pumps 70 are driven from the head.

By making the crank arm 40 separate from the crank shaft 30, there is secured not only the greater ease of assembly noted above, but also 75 ease of replacement of the crank arm. In this

way the stroke of the crank may be changed without disturbing the remainder of the unit or the adjustment of the heavy gearing.

To provide a tight lubricating system for pressure lubrication, all of the bearing joints are 5 protected by seals, such as the head 48 over the wrist pin 43, or the ring 49 surrounding the hub of the head 44, or the ring 50 surrounding the flanged disc 39 of the shaft 30.

The lubricating system employed with this unit 10 is, in general, somewhat similar to that disclosed in the patent above identified, and provides direct flow of oil under pressure to all joints and moving parts, excepting those which are immersed below the oil level 14 in the reservoir 13 15 of the lower casing. To provide pressure for this lubricating system, an oil pump 51 is provided. In the present case, this pump 51 is located below the level 14 of the oil in the reservoir 13 so that a constant supply of oil to the pump will be insured 20 and so that there will never be necessity for priming the pump. The pump 51 is driven through a small pinion gear 52, preferably carried by the pump itself, and receiving its power from a larger gear 53 attached to the under side of the 25 bevelled gear 21 on the shaft 19. Oil from the pump 51 discharges into a pressure chamber 51' from whence it is distributed, under pressure, to various moving parts of the unit, as in the patent 30 identified above.

Novel mounting means is provided for the entire unit. A sole plate 54 in the form of a beam or rail of metal is securely fastened to a foundation 55, preferably by imbedding it in concrete. The lower casing 11 of the housing has a heavy metal 35 flange 56 extending from it horizontally, at about the center line of the housing. The housing 10 is set into the sole plate 54 so that the lower casing 11 extends down into a depression or recess 51 within the confines of the sole plate, and so 40 that the entire unit is carried by the flange 56 which rests upon the sole plate 54. Corresponding bolt holes 58 on the flange 56 and the sole plate 54 are then brought into register, and heavy bolts 59 are passed therethrough to securely fasten 45 the housing to the sole plate.

By virtue of the novel mounting means described above, the entire unit, or any of the parts thereof, may be easily and quickly removed when necessary for inspection or replacement. Moreover, by making units of various power capacities 50 with the same size flange, it is relatively simple to exchange one unit for another of different capacity, without in any way damaging the units or disturbing the foundation.

It will be noted that both the lower casing 11 and the cover plate 12, which is securely bolted thereto, are formed with heavy ribs 60 and 61 which add greatly to the strength of the housing 10. It may thus be seen that the housing 10 and the sole plate 54 provide a solid, secure 65 mounting for the unit, capable of withstanding the terrific loads imposed thereon. It will be noted also that the flange, by which the unit is mounted, is positioned above the lower bearing 65 of the crank shaft 30 in the vicinity of the midpoint between the upper and lower bearings thereof. By this means there is secured better balance and stability for the unit, and the strains upon the housing are divided and minimized.

Various changes may be made in the embodiments of the invention hereinabove specifically described without departing from or sacrificing the advantages of the invention as defined in the appended claims.

I claim:

1. In a driving unit, the combination of a bottom casing, a vertical crank shaft within said casing, speed reducing gearing including a gear upon said shaft, a bearing for the upper end of said shaft, a cover for said casing passable downwardly around said bearing and releasably secured to said casing, and means coacting with said shaft and said cover to suspend said shaft from said cover.

2. In a driving unit the combination of a bottom casing, a cover removably affixed thereto, a vertical crank shaft journalled in said casing at its lower end, a gear on said shaft, a thrust bearing supporting the upper end of said shaft, a sleeve carrying said bearing and slideable through said cover, and a ring supported by said cover and engaged with said sleeve to thereby suspend said shaft.

3. In a driving unit the combination of a housing having a cover, a vertical shaft journalled at its lower end in said housing, speed reduction gearing including a gear on said shaft, a thrust bearing supporting the upper end of said shaft, a sleeve carrying said bearing and mounted in said cover for vertical movement, and a ring seated on said cover surrounding said sleeve and in screw threaded engagement therewith for adjusting said shaft and said gear vertically within said housing.

4. In a driving unit, the combination of a housing, a shaft in said housing, a bevel gear on said shaft having a face at an angle of more than 45° to said shaft, a bevel pinion engaged with said bevel gear, a thrust bearing for one end of said shaft, a sleeve supporting said bearing and mounted in said housing for movement axially of said shaft, and a ring seated on said housing surrounding said sleeve and in screw threaded engagement therewith, for adjusting said bevel gear relative to said bevel pinion.

5. In a driving unit for oil wells the combina-

tion of a housing, a vertical crank shaft journalled in said housing, speed reducing gearing for driving said shaft, a cover for said housing passable downwardly around the end of said shaft and forming the only lateral bearing support for the upper end of said shaft, and a crank arm releasably secured to the upper end of said shaft above said cover.

6. In a driving unit for oil wells the combination of a housing, a removable cover for said housing, a vertical shaft journalled in said housing and said cover and projecting above said cover, speed reducing gearing in said housing for driving said shaft, a crank arm mounted on the projecting upper end of said shaft above said cover and projecting laterally over said cover, said crank arm being supported and centered by said shaft and being releasably secured thereto to permit removal of said crank arm and said cover.

7. In a driving unit the combination of a housing, a vertical shaft within said housing, speed reducing gearing including a gear on said shaft for driving the same, a disc at the upper end of said shaft, a cover for said housing passable downwardly around said disc and the end of said shaft, said shaft being journalled at its lower end in said housing and having its upper end journalled in said cover and centered solely thereby, and a crank arm releasably secured to said disc.

8. In a driving unit for oil wells the combination of a housing, a vertical shaft within the housing, driving means for said shaft, a removable cover for said housing passable downwardly around said shaft, said shaft being journalled at its lower end in said housing and at its upper end in said cover and being unsupported between said points, and crank means removably secured to the upper end of said shaft above said cover.

WALTER P. SCHMITTER.
